No. 608,344.

Patented Aug. 2, 1898.

F. P. NESMITH.
SURGE RELIEVER.

(Application filed Sept. 4, 1897.)

(No Model.)

UNITED STATES PATENT OFFICE.

FREDERICK P. NESMITH, OF PORTLAND, MAINE, ASSIGNOR OF TWO-THIRDS
TO MELVILLE W. TREFETHEN AND CHARLES N. TREFETHEN, OF SOUTH
PORTLAND, MAINE.

SURGE-RELIEVER.

SPECIFICATION forming part of Letters Patent No. 608,344, dated August 2, 1898.

Application filed September 4, 1897. Serial No. 650,566. (No model.)

To all whom it may concern:

Be it known that I, FREDERICK P. NESMITH, a citizen of the United States of America, residing at Portland, in the county of Cumberland and State of Maine, have invented certain new and useful Improvements in Surge-Relievers; and I do hereby declare the following to be a full, clear, and exact description of the invention, such as will enable others skilled in the art to which it appertains to make and use the same.

My invention relates to improvements in surge-relievers, and especially to that class of surge-relievers which may easily and readily be attached to either the deck or the rail of a vessel and also readily attached to the main-sheet, so as to take away from the main-boom and the bits to which the main-sheet is attached the greater part of the strain.

To this end it consists of a cylinder or sleeve having removable plates in the ends thereof, a suitable metallic spring within said case, means for causing said spring to be compressed, and means for attaching the device to the rigging and to the vessel.

In the drawings herewith accompanying and forming a part of this application, Figure 1 is a plan view of my improved device. Fig. 2 is a horizontal section showing the arrangement of the movable staple. Fig. 3 is a horizontal section showing the manner of attaching the fixed rods to the head of the confining-case, and Fig. 4 is a perspective view showing the application of my improved device.

Same letters refer to like parts.

In said drawings, A represents a cylindrical confining-case or sleeve. Set in one end and held there by means of screws B or similar means is a cap C. Mounted in said cap C in such a manner that it may swivel therein is a hook D, having a shank E set within the socket F in said cap C and held there by means of a nut or other suitable means, as seen at G. The purpose of allowing this hook to swivel will be hereinafter more fully set forth. Within said casing or sleeve A is a spring H, which I preferably make with square surfaces. I use a spring with square surfaces, so as to obtain more power, and at the same time by

using a spring with square surfaces one member of the spring when the spring is tightly compressed cannot ride over its adjacent member. I do not wish to limit myself to a coil-spring with flat surfaces, for a spring composed of round members would do the work nearly as well. Said spring is wound around two rods I, which on one end are firmly attached to the cap C in any suitable manner and are provided on the other end with nuts J. In order to prevent the spring from slipping on the said rod, I insert between the nuts J and one end of the spring a washer or keeper K. There is also attached to the cylinder, at the opposite end thereof, another cap L, provided with two openings M. Inserted within said openings and adapted to move easily therein is a staple N, the straight members N' of which extend through said cap into the cylinder and within the coil of the spring nearly to the opposite end of the confining-case and parallel with the rods I, but in a different plane. On the ends of this staple is placed a keeper or washer O, and in the ends of the said staple are placed nuts P for the purpose of holding said keeper in position. Attached to the staple and outside of the casing is a hook Q, of any desirable form or shape, provided with a tongue R, so that the main-sheet or any other rope on a boat may be inserted therein and kept in position without the danger of the same being thrown out.

The operation of my improved device is as follows: The surge-reliever is attached either by a ring-bolt or eyebolt to the after part of the vessel, preferably at or near the stern rail. The main-sheet is then led from the traveler through the ring in the end of the device and made fast to the bit or cleat. When there is pressure on the main-sheet, the position of the surge-reliever will be the same as shown in dotted lines in Fig. 4. When the pressure on the sheet has been released or has been removed, the position of the surge-reliever would be as shown in Fig. 4 in solid lines. When it is desired to gibe the vessel, it will be seen that the surge-reliever will take up some of the slack of the sheet as the boom changes its position from one side to the other. Then when the sail is changed to the other

side of the vessel and the strain once more comes upon the sheet, it will be seen that by the compression of the spring in the confining-case the jar and sudden shock or strain on the boom and on the bit to which the end of the main-sheet is made fast will be relieved, with the result that there will be no sudden check or jar.

- 5 It is quite essential that the hook Q should be kept in such a position that the tongue R may always be on the upper side thereof, so that the main-sheet or other rigging may be readily inserted therein or removed therefrom. It is for this purpose I make the hook 10 D capable of swiveling, so that whenever the same is attached to a ring or eye bolt or made fast in any other way to a vessel the said tongue R may be always kept on the upper side of the hook Q.
- 15 20 The object of my invention is to provide a simple, inexpensive, and durable device to relieve the strain upon the rigging and spars of a vessel.

Having thus described my invention and its 25 use, I claim—

1. In a surge-reliever, in combination, a confining-case, a compressible spring within said confining-case, a hook swiveled in one end of said confining-case, a staple with a snap-hook

on one end running through said spring and 30 provided with a keeper and suitable nuts on the other end thereof, rods rigidly attached to the other end of said casing and running through said spring, the said rods being provided with a keeper and means for holding 35 said keepers in position, substantially as and for the purposes set forth.

2. In a surge-reliever, in combination, a confining-case, a compressible spring within said confining-case, caps in the ends of said case, 40 a hook swiveled in one cap, rods running from said cap within the confining-case and through the spring, a staple, with a snap-hook thereon, running through the other cap within the confining-case and through the spring, 45 the free ends of said staple and said rods being provided with keepers and means for holding said keepers against the free ends of the spring, substantially as and for the purposes set forth.

50 In testimony whereof I affix my signature, in presence of two witnesses, this 1st day of September, A. D. 1897.

FREDERICK P. NESMITH.

Witnesses:

NATHAN CLIFFORD,
HARRY F. NESMITH.
